UNITED STATES PATENT OFFICE.

ROY J. CARRIER, OF CHICAGO, ILLINOIS, ASSIGNOR TO HOWE AND DAVIDSON COMPANY, OF CHICAGO, ILLINOIS, A CORPORATION OF NEW JERSEY.

MACHINE FOR PARAFFINING PAPER.

SPECIFICATION forming part of Letters Patent No. 737,826, dated September 1, 1903.

Application filed March 31, 1902. Serial No. 100,700. (No model.)

To all whom it may concern:

Be it known that I, ROY J. CARRIER, of Chicago, in the county of Cook and State of Illinois, have invented certain new and useful 5 Improvements in Machines for Paraffining Paper; and I do hereby declare that the following is a full, clear, and exact description thereof, reference being had to the accompanying drawings, and to the letters of reference marked thereon, which form a part of this specification.

This invention relates to improvements in machines for applying paraffin to paper preparatory to forming such paper into cartons 15 or boxes, said machine being of that class embracing a receptacle for the paraffin-bath, a roller which dips into the bath and carries the paraffin from the bath to the paper, and a second roller or abutment between which and the 20 paraffin-applying roller the paper is pressed.

The invention refers more specifically to an improvement in paraffining-machines designed to leave on the sheet or sheets of paper unparaffined strips or areas which 25 constitute the marginal parts of the carton-blanks when cut from the paraffined paper and which are adapted to receive the adhesive material by which the side walls of the boxes or cartons are joined when set up.

30 The invention consists in the matters hereinafter set forth and more particularly pointed out in the appended claims.

In the drawings, Figure 1 is a plan view of a machine embodying my improvements, showing a sheet of paper in position to be paraffined thereby, said sheet of paper and parts of the machine being broken away. Fig. 1^a is a fragmentary section taken on line 1^a 1^a of Fig. 1. Fig. 2 is a view, partially in longitudinal section and partially in elevation, taken on line 2 2 of Fig. 1. Fig. 3 is a transverse section taken on line 3 3 of Fig. 2 looking toward the rear of the machine. Fig. 4 is a vertical section taken on line 4 4 of Fig. 3. Fig. 5 is an enlarged vertical section taken on line 5 5 of Fig. 1. Fig. 6 is a fragmentary section taken on line 6 6 of Fig. 1.

As shown in said drawings, A designates an open-topped receptacle or pan adapted to

contain the paraffin-bath and supported on 50 upright standards A' A', which latter rest on the floor or a suitable base. The pan is provided with a heating-coil A², by which the paraffin is maintained in a suitably-heated condition.

B B' designate upper and lower rollers, the latter of which dips at its lower part into the paraffin-bath and carries the paraffin to the under surface of the strip or sheet of paper C, passing between the rollers, the upper 60 roller serving to press said paper against the lower or paraffining-roller. The rollers are provided with shafts b b', and the ends of the shaft b of the upper roller are seated in stationary bearings in the upper ends of suitable bearing boxes or standards B². The lower shaft b' is mounted at its ends in split or two-part bearings B³, which are seated in yokes B⁴, pivoted at their rear ends to short stub-shafts b². Said yokes are provided with 70 horizontal arms B⁵, which receive the upward pressure of springs B⁶, interposed between the bottom of the paraffin-pan and the lower ends of screw-threaded studs or bolts extending vertically through said yoke-arms, as most 75 clearly shown in Fig. 5, whereby the lower roller is held yieldingly against the upper roller. An adjustable stop B⁸ limits the upward movement of the yoke-arm B⁵, said stop being screw-threaded and extending through 80 apertured lugs or projections b⁸ on the bearing standards or blocks B² and bearing at their lower ends on the upper margins of the said yoke-arms. The stops are provided at their upper ends with hand-wheels b⁴, by 85 which they are adjusted. Said roller-shafts b b' are provided at one side of the machine with intermeshing gear-wheels b⁵ b⁶, respectively, as most clearly shown in Figs. 1 and 7, and one of the shafts—the upper shaft b, as 90 herein shown—is provided outside of said intermeshing gear-wheels with a driving-pulley B⁹, through which power is applied to operate the machine.

D designates a transverse doctor-roller 95 mounted in suitable bearings in the lower parts of the bearing-blocks B² and pressing against the lower or paraffin roller, below the

axis thereof, for removing the surplus paraffin from the roller B', and thereby regulating the amount of paraffin applied to the paper. The shaft of said roller is rotatively mounted in 5 movable bearing-blocks D', which are moved toward the roller by means of adjusting-screws d, which have screw-threaded engagement with the apertures in the bearing-blocks B² and which bear at their ends against said 10 movable bearing-blocks. Said rollers are faced with a suitable porous or absorbent material, preferably felt or like fabric. Such facing acts more effectively than a non-absorbent facing to take up the surplus material 15 from the paraffin-applying roller.

The paraffining-roller B' is provided between its ends and centrally thereof, as herein shown, with an annular groove or depression b⁷, which constitutes an interruption in 20 the paraffin-applying surface of the roller, so that as the sheet or strip of paper passes between the rollers B and B' a narrow strip or area of the paper intermediate the side margins thereof remains unparaffined. Said unparaffined strip or area is made of such width 25 as to constitute two pasting strips or flaps of two carton-blanks cut from the paper on opposite sides of said unparaffined strip or area. It will be understood that after the strip C of 30 the paper has passed through or between the rollers B B' and the under surface has been paraffined, except for the central strip or area thereof, it is cut transversely into sheets or sections of suitable length for handling, and 35 said sheets or sections are thereafter longitudinally and transversely cut or severed to form a plurality of blanks for cartons to be cut therefrom. Said sheets or sections after being paraffined and cut from the main body 40 of the paper in the manner described contain material for a plurality of carton-blanks arranged in laterally-separated pairs, the blanks of each pair being adapted to be divided along the longitudinal center of the 45 unparaffined strip or area, so as to leave an unparaffined strip or margin on each blank, the sheets or sections being divided to form a number of pairs of carton-blanks. The cutting of the blanks from the section so cut 50 from the strip may be effected in any suitable manner, and in practice this work is done in a suitable press having cutting-dies which give proper form to the carton-blanks as the sections pass through the press. It will thus 55 be seen that each section or sheet cut from the main body of the paper after it is paraffined is of a width equal to that of two blanks and because of its width may be relatively long, and thereby adapted for the cutting 60 therefrom of a relatively large number of blanks. A sheet thus made of a width and length required for a number of blanks may be conveniently and economically handled as a whole, whereby the expense of handling the 65 stock is reduced largely as compared with that required when the sheets are made with a single unparaffined strip at one edge thereof

and one row of blanks only is cut from each sheet. Furthermore, by reason of the fact that a greater number of blanks may be contained and handled in a unit section the carton-blanks may be much more rapidly formed than by the process heretofore employed. 70

E designates a scraping device, which bears at its forward end on the paraffining-roller 75 above the axis of the latter at the part of said roller containing said groove b⁷, said scraper extending on each side of said groove a short distance, as most plainly seen in Fig. 1. Said scraper E is provided with a shank E' at its rear end, which is connected by a bolt e with an upper forwardly-projecting arm of a bracket A³, attached, as herein shown, to one of the coil-pipes A². Said shank E' is provided with a slot, as shown in Fig. 1, whereby the position of the scraper with respect to the roller may be varied to adjust the same to the roller. Said scraper serves to prevent the accumulation of paraffin at the angles between the face of the roller and the shoulders 85 at either side of the annular groove or depression therein. If such scraping device be not present, the paraffin tends to accumulate on the edges of the roller at the sides of said groove and would result in a surplus quantity of paraffin being deposited at the sides of the unparaffined strip or area of the paper, which would be liable to spread upon such strip or area or would form objectionable ridges at the sides thereof. Said scraper, however, prevents such accumulation, so that the line of demarcation between the paraffined and unparaffined area of the paper will be sharp and well defined. A further purpose of the scraper-plate is to prevent the paraffin being thrown upwardly 90 by the centrifugal action from the ascending side of the roller against the under surface of the paper and which would act to splash or partially cover the section or area designed to remain unparaffined. 95

The roller B' may be provided with a number of said grooves or depressions b⁷ throughout its length, so as to form unparaffined strips at varying distances apart, whereby cartons of several different widths may be cut therefrom. In the drawings one end of the roller is shown as provided with an annular rabbet, which serves to leave an unparaffined strip or area on the edge of the strip C when said sheet is wide enough to extend beyond said 115 rabbet. When said rabbet is not to be used, it is filled with a spring filling-ring b⁸, as shown in Fig. 1, which when in place is flush with the cylindric surface of the roller B'. Other grooves of the roller may be similarly 120 filled with the filling-rings b⁸ when not in use. It will of course be understood that when the rabbets at the end of the roller or other grooves of the roller are brought into use a like number of scraping-plates E are employed, which 125 are adapted to severally act on the roller at the sides of the shoulders formed by the grooves or rabbets. Said plates are detachably and adjustably affixed to the machine, 130

so that they may be shifted longitudinally of the roller or removed from the machine, as desired.

When the roller is provided with more than 5 one groove or when its ends are provided with rabbets, such a roller is of course adapted for making blanks of definite or standard widths. An important advantage gained by the use of a grooved roller adapted to leave an uncoated 10 area at the middle of the paper is that such a roller is adapted for operating on a strip of any width less than the length of the roller.

By the use of the particular arrangement shown in Fig. 1 a strip of paper may be paraffined to be divided into three or more lateral sections, the intermediate unparaffined strip or area constituting when the strip is divided the pasting strips or flaps of the cartons, made from two of the longitudinal sections, while 20 the extreme margin of the paper, which is not paraffined, constitutes the pasting-margin of the third section, the material between said free margin and the intermediate unparaffined area or section being cut to divide one 25 marginal section of the paper from the adjacent or intermediate section.

Means are shown for feeding the strip of paper to the paraffin-rollers from a roll of paper C' and for guiding said paper so as to 30 maintain the central unparaffined strip or section parallel with the side margins of the paper. These devices are made as follows:

F designates a transverse shaft on which the roll C' of the paper is mounted. Said 35 shaft is mounted in the upper ends of two upright standards F' F², said standards being equipped with upwardly-opening or half bearings in which the ends of the shaft are seated. The standard F² is provided with a shiftable 40 bearing-block F³, in which the shaft is mounted, and said block is adjustable by means of a hand-actuated screw F⁴, which has rotative connection with a lug f, rising from the standard F², and has screw-threaded engagement 45 at its inner end with a similar lug f', rising from the block F³. In order to permit the opposite end of the shaft F to adjust itself to changed positions of the block F³, the bearing-block on the standard F' is connected with 50 the same by a vertical pivot in the manner shown in Figs. 1 and 3. The adjustment described is to enable the shaft F to be maintained substantially parallel with the paraffining-roller and the guiding devices for the 55 paper, as will hereinafter more fully appear.

The machine is provided between the shaft F and the paraffining-roller with a guide-roller G, the shaft g of which is mounted at its ends in rearwardly-projecting and upwardly-directed arms A⁴, connected at their forward ends with the paraffin-pan. Said guide-roller is provided near its ends with collars g', provided with guide-flanges g², by which the path of the paper is maintained 60 straight through the machine. Said collars are connected with the shaft by means of set-screws g³ passing through the collars and im-

ping at their lower ends against the roller, whereby said guide-rollers may be adapted 70 for strips of paper of varying widths.

Means are provided for moving the shaft F endwise in its bearings to maintain the path of the paper parallel through the machine notwithstanding the fact that the paper may be rolled unevenly. The construction by 75 which such endwise movement of the shaft is effected is as follows:

H designates a vertically-oscillatory lever which swings toward and away from the roll and is pivoted at its lower end to an arm H', 80 projecting inwardly from the adjacent standard or pillow-block F². Said arm is shown as provided with a curved slotted guide-segment H³, and the lever is provided with a guide lug or bolt h, which extends through and has 85 guiding engagement with the said slotted segment. The lever is provided above the segment with a forwardly-directed lug h', which is adapted to enter the space between two collars F⁶ F⁶, affixed to the shaft F, as more 90 clearly seen in Figs. 1 and 3, the space between said collars constituting a groove into which said lug h' extends. With this construction when the lug h' of said lever occupies the groove in the shaft and the lever is 95 swung vertically toward and away from the standards it acts to shift the shaft F and the roll C' of paper carried thereby longitudinally of the shaft. When the machine is in operation, an attendant manipulates the lever H' 100 to maintain the sheet in a straight path of travel, directing the sheet by the aid of the flanges g² on the guide-roller G. It is not intended that the edges of said sheet shall have guiding contact with the said flanges; but 105 said flanges are provided to enable the operator to properly guide the sheets by sight between the same and over said guide-rollers. The bar H', to which the lever H is pivoted, is shown as having swiveling connection with 110 the standard F² to permit the lever H to be swung outwardly away from the shaft F when the shaft is to be removed for placing a roll of paper on the shaft.

A tension device is provided acting on the 115 shaft F' to place tension on the shaft and paper and to prevent the paper from unwinding too freely from the roll, whereby the guiding of the paper may be more readily accomplished. Said tension device is shown most 120 clearly in Figs. 2 and 3 and consists of a grooved pulley I on the end of the shaft F outside of the standard F² and a flexible band I', which passes around said pulley. Said strap I' is connected at its lower end with 125 a screw-shaft I², which extends through an opening in a horizontal arm or projection I³ on the standard F² and which shaft is provided at its lower end with a hand-wheel I⁴.

I claim as my invention—

1. A machine for applying paraffin to paper comprising a paraffin-applying roller, the applying-surface of which is interrupted by a shoulder in the path of the paper whereby

a narrow strip of the paper passing through the machine is left unparaffined, a roller upon which the paper is wound and from which it is unrolled as it is fed to the paraffin-rollers, means for shifting said roller endwise and a horizontal guide between said paper-roller and the paraffin-roller provided with laterally-separated guide projections between which the paper passes and by means of which it is laterally guided.

2. A machine for applying paraffin to paper comprising a receptacle adapted to contain a paraffin-bath, coacting rollers between which the paper is adapted to pass, one of which rollers is adapted to dip into the bath to carry the paraffin to the paper and is arranged to leave on said strip of paper, parallel with the margin of said paper, an unparaffined strip or area, a transverse shaft for carrying a roll of paper, means for shifting said shaft transversely of the machine to guide the paper, and a guide-roller between said shaft and the paraffin-roller provided with guide projections between which the strip of paper passes.

3. A machine for applying paraffin to paper comprising a receptacle adapted to contain a paraffin-bath, coacting rollers between which the paper is adapted to pass, one of which rollers is adapted to dip into the bath to carry the paraffin to the paper and is adapted to leave on said strip of paper an unparaffined strip or area parallel with the margin of said paper, a transverse shaft for carrying a roll of paper, means for moving said shaft transversely of the machine to guide said paper, and a guide-roller between said shaft and the paraffin-roller provided with guide projections between which the strip of paper passes, said guide projections being adjustable longitudinally of the roller to adapt the roller to strips of paper of varying widths.

In testimony that I claim the foregoing as my invention I affix my signature, in presence of two witnesses, this 19th day of March, A. D. 1902.

ROY J. CARRIER.
